Adolph Moritz

Montague Witt

Attorney

UNITED STATES PATENT OFFICE.

ADOLPH MORITZ, OF ATLANTA, GEORGIA.

TIE-LOCK SEAL.

Application filed May 19, 1925. Serial No. 31,255.

To all whom it may concern:

Be it known that I, ADOLPH MORITZ, a citizen of the United States, residing at Atlanta, in the county of Fulton and State 5 of Georgia, have invented certain new and useful Improvements in Tie-Lock Seals, of which the following is a specification.

The present invention relates to improvements in a sealing means and more particularly those in connection with freight cars. It comprises a seal which in its preferred form is applied to any freight car door of standard construction and is so devised that it will readily disclose any evidence of 10 molestation.

A further object of the present device relates to a seal so constructed that both ends will be securely interlocked and ample space will be left on the ends to provide for road 15 or business names or initials and seal numbers or symbols.

For the attainment of these ends and the accomplishment of other new and useful objects, as will appear, the invention consists in the features of novelty in the construction, combination and arrangement of the several parts generally shown in the accompanying drawing and described in the specification, but more particularly pointed 20 out in the appended claims, in which:—

Figure 1 is a plan view showing the seal embodying the present invention before it is interlocked.

Figure 2 is a plan view illustrating the 25 position of the ends after being thrust through the slot, and after the first bend of end 2 around and underneath the end 3.

Figure 3 is a plan view of the seal after the ends have been completely interlocked.

The sealing member 1 is preferably constructed from sheet or other similar metal of any desired length, and has formed on the opposite edges on the end 2 notches, preferably V-shaped 4 and 4' and 5 and 5', located intermediate the extreme end and the middle of the band.

The indentation or groove or scoring or chilling 9, across the metal between the notches 5 and 5' located intermediate the 45 extreme end 2 and the middle of the band is for the purpose of weakening the metal, and any other means would suffice for obtaining this purpose.

There is formed on the respective edges

of the opposite end 3 of the band notches 55 6 and 7, preferably in an elongated V-shape, located intermediate the middle of the band and the extreme end.

There is formed in the center of the end 3 of the band between the notches 6 and 7 60 a slot 8, preferably diagonal, of a width at least equal to the width and thickness of the band in order to receive the end 2.

There is ample space on end 2 and end 3, both, intermediate between the slot and 65 locking notches and the extreme ends of the band to provide for any labelling of names, initials or numbers as may be desired to place on the respective ends.

When the end 2 of the band is inserted 70 through the slot 8 the notch 4' on the right edge of the end 2 of the band will interlock with the edge of the upper end 10 of the slot 8 and will positively hold the right notch 4' securely engaged with the slot. 75

When the first bend is made of the end 2 around and underneath the end 3 at notches 5 to 5' the indented, grooved, scored, chilled or weakened reduced portion 9 will seat in notch 6 on the right edge of end 3 of the 80 band.

When the second bend is made of end 2 around and over end 3 the bend 11 will seat in notch 7, and engage with edge of end 2 at notch 4. 85

The manner of operation of the seal to a locked position will be evident from the above description. The band will be inserted through a hasp or other members and the end 2 drawn through the slot 8 until 90 the notch 4' reaches the slot. It will then be moved upward to engage the upper end 10 of the slot and then bent down over the edge of notch 6 at the indented, grooved, scored, chilled or weakened reduced portion 95 9, to cause a break of the material between the notches 5 and 5' when unbent. After it has been so bent underneath the end 3 it will be bent over the end 3 at line 11, the end 2 fitting and interlocking at this point 100 within the left notch 7 of end 3 and notch 4 of end 2.

While I have above described what I have found to be a very practical embodiment of my invention, it is nevertheless to be understood that it may also be exemplified in numerous other alternative constructions and I accordingly reserve the right of adopting 105

all such legitimate constructions as may fairly be embodied within the spirit and scope of the invention as claimed.

I claim:—

- 5 1. A sealing band having a diagonal slot near one end, the other end being adapted for passage thru said slot and to be bent around the first-mentioned end, and locking means located near said ends to hold the ends in locked relation when the said other end is passed thru said slot and bent around the first-mentioned end.
- 10 2. A sealing band having a diagonal slot

therein, notches in the side edges of the band adjacent the slot, one end of the band being adapted for passage thru said slot and to be bent around the band to engage said notches, said band having notches near said one end adapted to interlock with the slot and notches adjacent thereto, the band having therein a weakened portion near the said one end, whereby the band when locked cannot be unlocked without breaking at said portion.

In testimony whereof I affix my signature.

ADOLPH MORITZ.
